UNITED STATES PATENT OFFICE.

WILLIAM J. STEENROD, OF BENTON HARBOR, MICHIGAN, ASSIGNOR TO BAKER-VAWTER COMPANY, OF BENTON HARBOR, MICHIGAN, A CORPORATION OF MICHIGAN.

LOOSE-LEAF BINDER.

Application filed August 20, 1923. Serial No. 658,297.

To all whom it may concern:

Be it known that I, WILLIAM J. STEENROD, a citizen of the United States, residing at Benton Harbor, in the county of Berrien and State of Michigan, have invented certain new and useful Improvements in Loose-Leaf Binders, of which the following is a specification.

My invention relates to loose leaf binders of the class in which one of the binder covers is provided with a hinged clamping bar equipped with binder posts adapted to receive the orificed leaves of the book, and the other cover is provided with an orificed binding member equipped with locking mechanism arranged to cooperate with the posts. One object of my invention is the provision of novel locking mechanism of the ball and wedge type exhibiting novel features of construction contributing to the usefulness and desirability of the device in the way of convenience of manipulation in releasing the locking mechanism, simplicity in the construction of posts and ease in assembling them; and another object is the provision of means for preventing the cover and clamping bar carrying locking mechanism (which locks in one direction only) from slipping down on the posts after the mechanism has been unlocked and the cover lifted to an elevated position in which it is desired to maintain it. With the foregoing objects and incidental advantages in the construction and arrangement of parts in view I have devised and invented the loose leaf binder mechanism hereinafter described in detail and illustrated in the accompanying drawings, the essential elements of my invention being more particularly pointed out in the appended claims.

In the drawing forming a part of this specification and exhibiting the construction of my invention in a preferred form, Figure 1 is a longitudinal section of the hinged clamping members of a loose-leaf binder provided with my invention, centrally of the posts; Fig. 2 is a section at right angles to the plane of the section of Fig. 1, the cover being shown in elevated position; and Fig. 3 is a detail showing in perspective the releasing lever, detached.

The same reference characters indicate the same parts in all the figures of the drawing.

As usual in the class of binders to which my invention relates, the binder covers A are hinged to clamping bars B, which may conveniently consist of hollow sheet metal frames formed to receive the clamping and sheet-holding mechanism. In the present instance both bars are of the same construction, each including an outer longitudinally folded and flanged member 1 and a telescoping inner member 2, to the intermediate outer side of which is secured, by spot-welding or any suitable means one of the hinge plates 3 by which the covers 4 are connected with the clamping bars. In the ends of the clamping bars are arranged cushion blocks S secured by screws and serving to provide a neat finish and maintain the parts in assembled relation. The lower clamping bar (referring to the position of the parts as illustrated) is equipped with the usual binder posts 6, and the upper bar is provided with a pair of locking mechanisms to which certain features of my invention particularly relate.

These mechanisms each include a wedge block 7, beveled on its outer lower edge to be received snugly within opposite faces of longitudinal bends in the inner clamping bar member 2, and having an inner conical wedging surface 7^a. Within the block 7 is arranged an annular ball-carrier 8, having a bottom flange 8^a formed with a plurality of orifices (three in the present instance) of such size that the balls 9 may project therethrough to grip the post. A coiled expansion spring 10 surrounds the ball-carrier and bears at its lower end against the top of the flange 8^a and at its upper end against the inner face of the top of a retaining cup 11 which slidily receives the ball-carrier and has a peripheral bottom flange 11^a extending underneath the outer upper plate 1 of the clamping bar and seating upon the upper face of the wedge block 7.

The ball-carrier is provided at its top with a radially extending flange in the form of a collar 12 arranged to engage with the forked end of a releasing lever 13 having a stud 14 which projects inwardly from an intermediate bend in the lever through an orifice in the top plate member 1. By means of a finger piece 15 which forms the outer end of the lever, the lever may be rocked to elevate the ball carrier against the

stress of the spring and thus release the locking grip of the balls upon the binder post. The proportion and relation of the parts are such that by lifting the ball carrier to its 5 extreme outermost position (which can readily be done by means of the collar 12) the releasing lever can be disengaged and removed or replaced, although in the normal use of the mechanism it is not liable 10 to accidental disengagement.

As will readily be understood from the foregoing description, the clamping bar will be automatically clutched upon the binder posts when the bar is forced downwardly 15 against a body of interposed leaves, through the wedging action of the face 7^a of the wedge block against the balls in contact with the posts, in a manner well known to those familiar with this type of clutching or locking mechanism. The clutching engagement 20 may be readily disengaged, however, by lifting the bar while pressing, with disengaged fingers, upon the releasing lever.

Since the clutching mechanism permits 25 the bar to slide downwardly upon the posts, practically without resistance, even though the releasing lever be left free, I have provided means for yieldingly maintaining the bar in elevated position, consisting of a 30 pair of balls 16 confined within a transverse bore in the top member of the binding post and stressed apart by a spring 17. The opposite margins of the orifice are slightly constricted by a suitable tool after the balls 35 have been inserted, permitting a portion of each ball to project into the path of the margin of the orifice through the clamping bar members 2 and 3. A slight degree of positive force may be applied to force the 40 clamping bar past the balls, while the tension of the spring is sufficient to maintain the bar in upper position until such force is applied in order to overcome its resistance.

I claim:

45 1. In a loose leaf binder having covers and hingedly connected clamping bars, one of said bars being equipped with binder posts, clutching mechanism carried by the other bar arranged to cooperate with the posts, and comprising a wedge block seated in such bar and having a conical wedging face, a plurality of balls arranged to cooperate therewith, a spring-pressed ball-carrier arranged to stress said balls into engagement with said wedging face, and a 50 rocking lever operable to shift said carrier and balls into position of disengagement.

2. In a loose leaf binder having covers and hingedly connected clamping bars, one of 55 said bars being equipped with binder posts, clutching mechanism carried by the other bar arranged to cooperate with the posts, and comprising a wedge block seated in such bar and having a conical wedging face, a 60 plurality of balls arranged to cooperate 65

therewith, a spring-pressed ball-carrier arranged to stress said balls into engagement with said wedging face, said carrier having a radially extending collar at its outer end, and a rocking lever having a forked end arranged to cooperate with said collar and a finger piece at its opposite end operable to shift said carrier and balls into position of disengagement. 70

3. In a loose leaf binder having covers 75 and hingedly connected clamping bars, one of said bars being equipped with binder parts, clutching mechanism carried by the other bar arranged to cooperate with the posts and including a wedge block seated in said bar and having an inclined wedging face, ball-clutching means arranged to cooperate with said wedge block, a spring-pressed ball-carrier arranged to stress said ball-clutching means into engagement with 80 said wedging face, and a rocking release lever fulcrumed upon the outer face of said last-mentioned bar and having one end arranged to cooperate with said ball-carrier and having its other end formed to serve as 85 a finger piece. 90

4. In a loose leaf binder having covers 95 and hingedly connected clamping bars, one of said bars being equipped with binder posts, clutching mechanism carried by the other bar arranged to cooperate with the posts, and including a wedge block seated in said bar and having an inclined wedging face, ball-clutching means arranged to 100 cooperate with said wedge block, a spring-pressed ball-carrier arranged to stress said ball-clutching means into engagement with said wedging face, and a rocking release lever having an inwardly bent intermediate portion equipped with an engaging stud seated in said last-mentioned bar, said lever having one end arranged to cooperate with 105 said ball-carrier and having its other end formed to serve as a finger piece. 110

5. In a loose leaf binder having covers 115 and hingedly connected clamping bars, one of said bars being equipped with binder posts, clutching mechanism carried by the other bar arranged to cooperate with the posts and including a wedge block seated in said bar and having an inclined wedging face, ball-clutching means arranged to 120 cooperate with said wedge block, a spring-pressed ball-carrier arranged to stress said ball-clutching means into engagement with said wedging face, said carrier having a radially extending collar at its outer end, and a rocking release lever having an inwardly bent intermediate portion equipped with a stud seated in said last-mentioned bar, said lever being forked at one end to engage said collar and having the other end formed to serve as a finger piece. 125

6. In a loose leaf binder, clutching mechanism according to claim 5 in which the stud 130

of said release lever is arranged to be disengaged when said ball-carrier is positively held in outermost portion.

7. In a loose leaf binder having covers and hingedly connected clamping bars, one of said bars being equipped with binder posts and the other bar being orificed and equipped with wedging clutch mechanism arranged to clutch said posts when moved outwardly thereon and permit free inward movement, yielding retaining means carried by said posts and arranged to cooperate with the under side of said last-mentioned clamping bar when such bar is shifted on said posts outwardly past said retaining means.

8. In a loose leaf binder having covers and hingedly connected clamping bars, one of said bars being equipped with binder posts and the other bar being orificed and equipped with wedging clutch mechanism arranged to clutch said posts when moved outwardly

thereon and permit free inward movement, retaining means carried by said posts including a spring-pressed ball arranged to 25 yieldingly cooperate with the under side of said last-mentioned clamping bar when such bar is shifted on said posts outwardly past said retaining means.

9. In a loose leaf binder having covers and hingedly connected clamping bars, one of said bars being equipped with binder posts and the other bar being orificed and equipped with wedging clutch mechanism arranged to clutch said posts when moved 30 outwardly thereon and permit free inward movement, retaining means mounted in a cross bar in each post including a compression spring and a pair of oppositely stressed 35 balls arranged to yieldingly cooperate with the under side of said last-mentioned clamping bar when such bar is shifted on said posts outwardly past said retaining means.

WILLIAM J. STEENROD.
